CONNECTING BASE PLATE

Ignatius J. Israelski, Jersey City, N. J., assignor
to Federal Telephone and Radio Corporation,
New York, N. Y., a corporation of Delaware

Application January 20, 1945, Serial No. 573,795

2 Claims. (Cl. 173—328)

1

The present invention relates to a base plate used for mechanically and electrically interconnecting two electrical devices, such as a converter with a regulator.

Mounting one electrical device upon the top of the other, it could not be avoided that the wires of the electrical connections were exposed and consequently, when working with tools, short circuits damaged those devices.

It is, therefore, the main object of the present invention to provide box-like means in which the electrical and mechanical connections between two electrical devices are concealed and not easily accessible.

An additional object of the present invention is to provide box-like means for receiving the electrical and mechanical connections between two electrical devices, whereby the box is open at its bottom to be closed up by the flat surface of the electrical device on which the box is mounted.

It is another additional object of the present invention to provide a connecting box formed of a base plate with turned over edges thus being open at its bottom whereby the edges being pressed against the surface of the electrical device on which the base plate is mounted.

A further object of the present invention is to provide simple means which assure simple connection and easy removal of one electrical device from the other by quick mechanical and electrical connection and disconnection, respectively.

It is another object of the present invention to provide means for fastening the base plate to one electrical device which base plate is equipped with terminals electrically connected with the leads from the other electrical device.

It is a further object of the present invention to provide spring connections for mounting of another electrical device on the base plate, in order to have fast connecting and removing means.

It is still another object of the present invention to provide plug-like means for connecting the leads of one electrical device with spring contact means of the base plate and to connect said electrical device with the terminals receiving the leads from the other electrical device.

With these and other objects in view the invention will be clearly understood in the following description in connection with the accompanying drawings, in which:

Figure 1 is a plan top view of the connecting base plate;

Fig. 2 is a cross-section along the lines 2—2 of Fig. 1, and

2

Fig. 3 is a bottom plan view of the base plate. Figure 4 is a fragmentary cross sectional view of the regulator, showing one of the slotted bolts.

Referring now to the drawings, the interconnecting box formed as a base plate consists of a plate 1 of preferably metal sheet, the edges 2 of which are bent downwards as shown in Fig. 2, thereby providing a hollow body with an open base. Four lowered holes 3 are provided near the four corners of the plate 1 to receive screw bolts (in dotted lines) attaching the plate 1 securely to the surface 1a of an electric device, as a converter to which another electrical device, as a regulator, is to be connected. This other electrical device (not shown) has a three-point connection with the base plate 1 by fastening three springs 4 below corresponding holes 5 in the base plate 1, which holes are adapted to receive connecting bolts of the other electrical device, as a regulator.

On one side of the plate 1 a grommet 6 is provided which is adapted to introduce the leads of the converter to the terminals fastened to the base plate 1.

In order to provide the necessary four terminals for the electrical connection of the leads of the converter with the base plate 1 the latter is equipped with eight holes 7 arranged in four pairs (Fig. 3). Below the base plate 1, where the holes 7 are arranged, two insulating plates 9 and 10, respectively, are provided in spaced relation and are held in the distanced position by insulating tubes 8, which tubes 8 serve not only, as stated as distancing but also as insulating means. Four lugs 11 extending parallel in one direction and four springs 12 extending parallel in the other direction are provided between the two insulating plates 9 and 10. Rivets 13 extending through the base plate 1, the upper insulating plate 9, the insulating tubes 8, and the lower insulating plate 10, keep all these elements in proper position close to lower face of the base plate 1, whereby the tubes 8 insulate the rivets 13 from the lugs 11 and the springs 12. The base plate 1 has a longitudinal cutout 14 just above the ends of the springs 12 and the upper insulating base plate 9 is equipped with four openings 15 in order to receive electrical contacts 15a from the regulator to be mounted on the interconnecting base plate 1. Just above the four lugs 11 the base plate is equipped with another cutout 16 which has on one side a tongue-like projection 17. The cutout 16 can be covered by a special plate 18 by means of a screw 19. This cutout 16 is necessary to allow the electrical connection of the leads from the converter to the

four lugs 11 representing the terminals of the base plate 1 and after securing the latter connection the plate 18 covers up the cutout 14 and the terminals 11.

In order to connect the regulator with the converter, it is necessary to fasten the box formed as a base plate 1 to the surface of the converter by inserting screw bolts (Fig. 2, in dotted lines) into the holes 3 of the box, thereby using the surface of the converter as base for the box. Then the cable from the converter is drawn through the grommet 6 and the wires connected with the four lugs 11, then the plate 18 screwed on the plate 1 by means of the screw 19. In order to mount the regulator on the base plate 1, three slotted bolts 19a, shown in Figure 4 of the regulator 20a are inserted into the holes 5 of the base plate 1 and by turning the bolts 90° the regulator is automatically secured to the base plate 1 due to the springs 4. The four contact bolts of the regulator are inserted into the respective holes 15 of the upper insulating plate 9 through the cutout 14 of the base plate 1 and the mechanical and electrical connections with the base plate 1 and thereby with the converter is achieved. It is possible to remove the regulator in shortest time just by disconnecting the contact bolts of the regulator from the holes 15 and to turn the connecting bolts of the regulator 90°, whereupon the regulator can be removed merely by lifting from the base plate 1.

The construction according to the present invention provides a box tightly fastened to the plane surface of one of the electric devices, which box receives and covers up entirely the electric connection between the mentioned and another electrical device to be mounted on the flat box, yet still allows fast disconnection of the electrical and mechanical connection means of the said other electrical device. Thus a very simple interconnecting means between two electrical devices is achieved, which means contains all advantages aimed for in the connection of two devices.

While I have disclosed the principles of my invention in connection with one embodiment, it will be understood that this embodiment is given 45

by way of example only and not as limiting the scope of the invention as set forth in the objects and appended claims.

What I claim is:

- 5 1. A connecting base plate between two electrical devices, comprising a box open at the bottom, a top plate substantially flat, a plurality of terminals insulatedly fastened to said top plate within the box, a plurality of contact springs, each of which is connected with one of said terminals, said fastening and connecting means being such as to maintain both the terminals and spring contacts accessible through openings in said top plate, said contact springs being adapted 10 to receive contact bolts of one of the said electrical devices, and portions of said base plate being depressed from the plane of said top toward the plane of its open bottom, and perforated to 15 secure said plate to the substantially plane surface of the other one of said electrical devices.
- 15 2. A connecting plate according to claim 1, in which said top plate is provided with an opening near one edge for entering conductors to be united to said terminals and in which a removable cover 20 plate is provided for the opening affording access to said terminals.
